(57) **CLAIM**

The ornamental design for a shelf with light illumination device, substantially as shown and described.

DESCRIPTION

FIG. 1 is a perspective view of a shelf with light illumination device showing my new design;

FIG. 2 is a front side view of the shelf with light illumination device shown in FIG. 1;

FIG. 3 is a back side view of the shelf with light illumination device shown in FIG. 1;

FIG. 4 is a left side view of the shelf with light illumination device shown in FIG. 1;

FIG. 5 is a right side view of the shelf with light illumination device shown in FIG. 1;

FIG. 6 is a top view of the shelf with light illumination device shown in FIG. 1; and,

FIG. 7 is a bottom view of the shelf with light illumination device shown in FIG. 1.

The broken lines in the drawings depict portions of the shelf with light illumination device that form no part of the claimed design.

The narrow space between the broken line back surface and adjacent solid line edge forms no part of the claimed design.

1 Claim, 4 Drawing Sheets
